A. J. JACK AND D. E. BRAND, OF DES MOINES, IOWA.

Letters Patent No. 95,905, dated October 19, 1869.

IMPROVEMENT IN WATER-WHEELS.

The Schedule referred to in these Letters Patent and making part of the same.

To all whom it may concern:

Be it known that we, A. J. JACK and D. E. BRAND, of Des Moines, in the county of Polk, and State of Iowa, have invented a new and improved Water-Wheel; and we do hereby declare that the following is a full, clear, and exact description thereof, which will enable others skilled in the art to make and use the same, reference being had to the accompanying drawings, forming part of this specification.

This invention relates to improvements in water-wheels; and

It consists in the construction and arrangement of parts as hereinafter specified.

Figure 1 represents a sectional elevation of our improved wheel, taken on the line *x x*.

Figure 2 represents a top view, with a part of the upper rim removed.

Similar letters of reference indicate corresponding parts.

The bottom plate A, which is made convex in a considerable portion of the surface, in order to better direct the descending current or volume of water to the buckets, and the upper rim B, are connected together by the studs or posts C, which also serve for the pivot-bolts of the buckets D.

These buckets consist of thin plates of metal, set edgewise between the plate A and rim B on these pivots. From the said pivots to the inner ends they have plane surfaces, but from the pivots to the other ends they are curved inward upon a regular curvature. The latter parts are about half the length of the former, which are connected to radial arms E, jointed at the inner ends to bell-cranks F, pivoted at their angles to a notched disk G, fixed on the shaft H, all arranged as

the shaft H, and connected, at their inner ends, by rods I, to a sleeve, K, on the shaft above the wheel, capable of sliding up and down, and provided with a lever or other suitable means for sliding it.

The movement of this lever one way or the other will move the buckets correspondingly on their pivots, to open or close them, or to vary the amount of the openings.

When the sleeve is moved downward, the inner ends of the buckets are thrown outward and the outer ends inward, so that when the lapping ends of the buckets meet, they touch at two points, and form double joints, shutting off the water, which is admitted at the top by any suitable arrangement of penstock.

We have found, by practical application, that the curvature of the outer ends of the buckets, such as we have here represented, produces better results than any other form of buckets known to us.

Having thus described our invention,

What we claim as new, and desire to secure by Letters Patent, is—

1. The buckets D, each pivoted at the beginning of the curved outer termination, thence to the inner end being plane, as shown and described.

2. The buckets D, having the form shown, the rods E, and bell-cranks F, pivoted at their angles to the notched disk G, fixed on the shaft H, all arranged as specified.

A. J. JACK.
D. E. BRAND.
